UNITED STATES PATENT OFFICE

173,088

SHOE

Kasta Pette Razmo, Des Moines, Iowa

Application April 5, 1954, Serial No. 29,865

Term of patent 7 years

(Cl. D7—7)

To all whom it may concern:

Be it known that I, Kasta Pette Razmo, a citizen of the United States, residing at Des Moines, in the county of Polk and State of Iowa, have invented a new, original, and ornamental Design for a Shoe, of which the following is a specification, reference being had to the accompanying drawing, forming a part thereof.

Fig. 1 is a perspective view,

Fig. 2 is a top plan view, and

Fig. 3 is a side view of my shoe, showing my new design.

I claim:

The ornamental design for a shoe, substantially as shown.
